UNITED STATES PATENT OFFICE.

AUGUST B. PLUSHKELL, OF LOS ANGELES, CALIFORNIA.

LOOSE-LEAF BINDER.

Application filed February 23, 1921. Serial No. 447,013.

To all whom it may concern:

Be it known that I, AUGUST B. PLUSHKELL, a citizen of the United States, residing at Los Angeles, in the county of Los Angeles and State of California, have invented new and useful Improvements in Loose-Leaf Binders, and the following is such a full, clear, and exact disclosure of the invention that any one skilled in the art to which it appertains may make and use the same.

My invention pertains to binders of the ring type and is designed primarily to provide a simple, inexpensive and efficient means for permanently securing loose or unattached leaves in book form so they will lie flat when the book is opened.

In its preferred form the device combines some of the features and advantages of a loose leaf ring binder; and is particularly applicable to binders for permanent records, such as check books, closed account books and the like, where leaves are ordinarily not required to be withdrawn or replaced, yet will admit of the latter in case of necessity.

My foremost object in perfecting the present invention was to provide an inexpensive means for securing loose leaves, in a more or less permanent binder; wherein the binding or covers could be made up in quantity and the loose leaves later attached with a minimum of time and labor, thereby reducing the cost of the completed product to the lowest possible figure.

Essentially the invention comprises a binder or cover, forming a support, and a ring, or rings, attached thereto for retaining the sheets or leaves; and one of the primary features of the invention, as will later appear, resides in the formation of the ring itself.

The nature of the invention will be more fully set forth in the following specification, taken in connection with the accompanying drawings, wherein I have illustrated a preferred specific form, and in which:

Fig. 1 is a fragmentary plan view showing the application of my invention to a binder; Fig. 2 is a perspective view of one of the binding elements; Fig. 3 is a fragmentary end elevation of a binder showing my improved retaining elements as applied thereto.

Broadly speaking my invention comprises essentially the mounting of leaf-retaining elements, (hereinafter termed rings) gener-

ally designated by the numeral 10, on a suitable binder or covering, generally designated by the numeral 11. The binder 11 consists of top and bottom covers 12 and 13, connected together by a flexible back portion 14 to permit the covers to be opened and closed in the usual manner. While I prefer to use this type of covering or binder in connection with my retaining means, it is to be understood that the top cover 12 and the back 14 may be discarded if desired, and the rings 10 mounted on a single back or support 13. In case of the use of a binder consisting of covers and back, as shown, the rings will be mounted on the supporting cover in such position that when the covers are in closed relation the back portion 14 will contact with one side of the ring portion 15, as shown in Fig. 3.

Any number of the rings 10 may be mounted on the bottom cover 13; in some cases one being sufficient, and in other cases two or more being preferable. The binder 11 may be constructed of any suitable material usually used for such work, such as pasteboard, or other binding materials; this feature of the invention being important only in so far as it provides a suitable support or mounting for the ring 10.

The rings 10 are preferably of the configuration shown in the drawings; comprising essentially an inverted U-shaped ring portion 15, having a securing portion 16 formed integral therewith. The device may be constructed of any suitable material, such as steel or brass wire, or the like; in which case, the ring portion 15 is formed by bending one end, and the securing portion 16 is formed by flattening out the opposite end for a suitable distance, through which portion holes or perforations 17 are punched for the reception of rivets 18, by means of which it is rigidly secured to its support 13.

The ring portion 15 is preferably bent to the configuration shown in the drawings (see Fig. 2) being formed by bending one end of a piece of material upwardly and over in the direction of the opposite end and then downwardly, forming a ring which is substantially three-quarters of a circle from one end of which a straight portion 19 extends tangentially, and from the other end of which the securing portion 16 extends tangentially (see Fig. 3). This portion 15 is then twisted laterally until it extends in a plane at an angle with the securing por-

tion 16, thus forming a substantially inverted U-shaped ring portion (see Fig. 2) at an angle with the securing portion 16.

The extreme lower face 20 of the portion 19 is terminated at a point flush with or in a plane with the bottom face 21 of the securing portion 16; or in some cases it may extend slightly below the surface 21, in order to press tightly against the upper face of 10 the support 13 on which it is mounted. In any event it is preferable that the face 20 extend below the top surface 22 of the securing portion 16 in order that the loose leaves 23 when supported thereon, as will be 15 hereinafter explained, will not ordinarily become accidentally disengaged from the straight portions 19.

As above stated in the preferred form of my device the securing portion 16 extends at

20 an angle relative to the axis of the ring portion 15 (Fig. 2) this angle being fixed as desired, but for all practical purposes it will be substantially 45°. This will enable the

25 ring portion 15 to be most easily inserted through perforations 25 of the loose leaves 23, when in a thick pad or block, after which the securing portion 16 (which will extend beyond the ends thereof, as shown in Fig. 1) may be riveted or secured to the back 13.

30 It is clear that the angle between the ring portion 15 and the securing portion 16 need not be held to 45°, or substantially so, but may be formed at any angle which will permit inserting the ring portion 15 through a thick pad or block of leaves 23 (before attaching) and thereafter permit the securing portion to lie beyond the ends thereof (as in Fig. 1) for attachment to the supporting member 13.

40 In practical use the device will be ordinarily handled by taking a thick block or pad of the leaves 23, as shown in Fig. 3, stacked in a pile with their perforations 25 in register and the retaining elements 10 se-

45 cured thereto by first passing the portion 19 upwardly through the perforations 25, from the bottom, and slipping the ring portion 15 through to the position shown in Fig. 1; after which the retaining portion 16 may

50 be fastened to the back cover or support 13 by the rivets 18. Fig. 1 illustrates the leaves 23 retained by the ring 15 on one side of the securing portion 16, from which it is plain to be seen that it will be a comparatively simple matter to mount the retaining elements on supports by the rivets, after being applied to the leaves. This simplicity of application is one of the principal features of my invention.

60 It will be noted from reference to Fig. 3 that in practical use the leaves 23 will ordinarily rest on the top face 22 of the securing portion 16, when thrown to that side of the ring portion 15, thereby being supported 65 above the top face of the support 13, and

generally obviating the possibility of any of the leaves accidentally passing between the lower face 20 of the portion 19 and the said upper face of the support.

While the rings will ordinarily be constructed of steel wire, or a similar material, they may be constructed of a comparatively soft resilient metal, which will admit of the ring portions 15 being sprung sufficiently to raise the lower faces 20 of the portions 19 75 away from the upper face of the support 13, and permit leaves to be withdrawn therefrom after they are mounted on the support.

While I have shown and described a preferred embodiment of my invention, it is nevertheless to be understood that I reserve the right to make any changes or modifications in structure which come within the scope of the appended claims.

Having described a preferred form of my invention, I claim:

1. In a device of the character described, a leaf-securing member comprising a securing portion and a ring portion, said securing portion being adapted to be secured to a 90 supporting member and said ring portion being formed to pass through a thick pad of leaves at one time, by extending the securing portion at an angle between the plane of the ring portion and its axis. 95

2. In a device of the character described, a leaf-securing member comprising a securing portion having a relatively inverted U-shaped portion formed integral therewith by bending one end, the plane of said U-shaped portion lying at an angle of substantially forty-five degrees, with said securing portion with its free end in a plane with the bottom face of said securing member to engage the face of the member to which said leaf-securing member is attached. 105

3. In a device of the character described, the combination of a base and a leaf retaining member secured thereto, said leaf retaining member comprising a ring portion 110 and a securing portion, the plane of the ring portion extending at an angle with the securing portion sufficient to permit its passage through a relatively thick pad of leaves at one time, the free end of the ring portion being straight and of a length to engage the surface of the base. 115

4. In a device of the character described, the combination of a base member and a leaf retaining member secured thereto, said leaf retaining member comprising a ring portion and a securing portion, the ring portion and securing portion being relatively formed to permit the extension of the ring portion through a thick pad of leaves at one time 125 and so the securing portion will then extend beyond the edges of said leaves to permit its later attachment to the base.

5. In a device of the character described, the combination of a base member and a leaf 130

retaining member secured thereto, the leaf retaining member comprising a ring portion and a securing portion, the ring portion and securing portion being relatively formed to 5 permit the extension of the ring portion through a thick pad of leaves at one time and so the securing portion will then extend beyond the edges of the said leaves to permit its later attachment to the base, the free 10 end of the ring portion being straight and

of a length to engage the face of the base when the securing portion is attached thereto.

In witness that I claim the foregoing I have hereunto subscribed my name this 11th day of February, 1921.

AUGUST B. PLUSHKELL.

Witness:

VIRGINIA BERINGER.
